(57) **CLAIM**

The ornamental design for a user interface for a trim control system on a marine vessel, as shown and described.

DESCRIPTION

FIG. 1 is a perspective view of a first example of a user interface for a trim control system on a marine vessel;

FIG. 2 is a front view thereof;

FIG. 3 is a rear view thereof;

FIG. 4 is a top view thereof;

FIG. 5 is a bottom view thereof;

FIG. 6 is a right side view thereof; and,

FIG. 7 is a left side view thereof.

The broken lines represent portions of the user interface that are shown for purposes of illustrating environment and form no part of the claimed design.
